LIGHTING SYSTEM

Richard K. Squires, Oakland, Calif., assignor of
one-half to Walter T. Sconyers, Oakland,
Calif.

Application August 29, 1938, Serial No. 227,380

14 Claims. (Cl. 40—130)

This invention relates to lighting systems and is concerned more particularly with the provision of means for providing a novel lighting effect which is particularly useful in displaying indicia such as house numbers, names or advertising matter.

It is a general object of the invention to provide a novel method of illumination.

Another object of the invention is to provide improved indicia displaying means embodying a luminous gas as a source of light.

Another object of the invention is to provide a display device which can be readily adjusted to display the indicia from different sides.

Another object of the invention is to provide display means of a simple and inexpensive construction which can be economically manufactured and assembled.

Other objects of the invention will appear from the following description of a preferred embodiment thereof as illustrated in the accompanying drawing, in which:

Fig. 1 is a sectional elevation of a house number sign embodying the invention.

Fig. 2 is a transverse sectional view of the sign taken in the plane of the line 2—2 in Fig. 1.

Fig. 3 is a fragmentary sectional view illustrating a modified form of lens construction.

Fig. 4 is also a fragmentary sectional view showing a third form of the lens construction.

Generally, the lighting system of my invention provides for a novel and attractive lighting effect by modifying the light produced by a gaseous discharge device such as a neon tube, and the modification is preferably effected by both diffusing and magnifying the light. In the embodiment disclosed, the lighting system is employed to display indicia, such as a house number, and the structure incorporates several advantageous features contributing to ready adjustment of the sign as to the indicia to be displayed, and with reference to its location and the place from which it is seen, as well as in providing for economical manufacture and assembly of the sign.

Referring to Figs. 1 and 2, the display sign embodying my invention includes a frame comprising base 10 having U-shaped transformer casing 11 mounted thereon between respective end plates 12, which are seated on base 10 and at their upper ends support display cylinder 13 for rotative adjustment in a manner later described. Preferably, base 10, casing 11 and end plates 12 are molded from opaque plastic material and are constructed to provide for assembly thereof without the use of special fastening screws or bolts.

Base 10 (Fig. 2) is provided with longitudinal L-shaped slots 16 to receive respective longitudinal flanges 17 formed along the walls of casing 11, whereby casing 11 is assembled on base 10 by pressing the side walls thereof inwardly so that flanges 17 can enter slots 16, and then permitting the walls to spring outwardly to their normal position when flanges 17 move into interlocking engagement with the under-cut portions of the slots 16. End plates 12 have respective flanges 18 conforming with the stepped transverse contour of casing 11, and dimensioned to provide a press-fit within the walls of the casing with the outer surface of the casing in flush relation with the adjacent surface of the end plates. Because of the stepped contour of the casing side walls and the flanges 18 and the seating of the end plates on the base, end plates are held securely against movement in all directions except longitudinally of casing 11.

End plates 12 are provided at their outer ends with facing annular flanges 21 providing bearing portions to receive the reduced ends 22 of cylinder 13 to provide for rotative adjustment of the cylinder relative to the end plates. It will be seen that the operation of engaging end plates 12 with casing 11 also serves to effect engagement of the end plates with the cylinder.

Cylinder 13 comprises a cylinder segment 23 of an opaque plastic material and one or more lens segments 24 mounted in side by side relation between the edges of cylinder segment 23 and formed to provide a continuation of the cylindrical surface thereof. To provide an interlocking connection between the edges of cylinder segment 23 and lens segments 24, the edges of the lens segments are provided with V-shaped notches 25 to receive the complementary bevelled edges of segments 23, and segment 23 is formed with a slightly greater radius than the outer surface of lens segments 24 so that segment 23 must be sprung inwardly to engage within the notches 25.

Extending axially through cylinder 13 is a source of light which is preferably a gaseous discharge tube 26 which has its ends removably positioned in similar recesses 27 of end plates 12. Each end of tube 26 is in contact with strip 28 of conducting material which is molded in and extends downwardly thru plate 12 and is connected by wire 29 with a terminal transformer 30 suitably mounted within casing 11 on base 10 as by fastening screws 31. Apertures 32 in base 10 provide for the entry of a suitable connection from a source of current to the transformer.

Base 10 is provided with suitable apertures 33 by means of which it may be mounted on a bracket or wall so as to display the sign, and it will be noted that by virtue of the rotative adjustment of the cylinder the sign can be moved to any desired angle to display the lighted lens segments.

The lens segment may be formed of a transparent molded plastic, glass or other suitable material, and preferably have the characters or indicia, such as numerals 34, formed as molded depressions which may be filled with enamel or other suitable opaque or semi-opaque material. The inner surface of the lens segments is preferably serrated as indicated at 36 to provide a light diffusing means. If desired the lens segment may be concavo-convex as shown in Fig. 2, plano-convex as shown in Fig. 3, or double-convex as shown in Fig. 4. In some instances where the lens is closely adjacent the tube as shown in Fig. 4, for example, a reflecting surface 37 may be provided on cylinder segment 23 to insure an even light distribution over the lens surface.

By the combination of the gaseous discharge tube, which is preferably of the luminous tube type with a diffusing and magnifying means, there is produced a novel light effect which produces an even glowing appearance throughout the surface of the lens without any noticeable difference in the intensity of the light and without the neon tube itself being distinguishable. In addition, the provision of individual lens segments in the cylinder provides for easy installation of any desired indicia such as house numbers, although the entire lens may be made in one piece if desired. By virtue of the rotative adjustment of the display cylinder about the light source, the indicia to be displayed can be easily adjusted to a desired position so that the sign will be visible from the desired angle.

While I have shown and described a preferred embodiment of the invention, it is to be understood that the invention is capable of both variation and modification from the form shown. The scope of the invention, therefore, should be limited only by the scope of the claims appended hereto.

I, therefore, claim as my invention:

1. In a lighting system, a base having parallel slots therein, one side of each slot being undercut to provide a locking recess, a U-shaped casing having resilient side walls with edges flanged to engage in said recesses and maintain the casing in place by virtue of the resilient action of said walls, end plates on said base and having a press-fit with the ends of said casing, an indicia displaying cylinder supported for rotative adjustment between said plates, and a gaseous discharge tube extending through said cylinder and having its ends supported in said plates.

2. In a lighting system, a base having parallel slots therein, one side of each slot being undercut to provide a locking recess, a U-shaped casing having resilient side walls with edges flanged to engage in said recesses and maintain the casing in place by virtue of the resilient action of said walls, end plates on said base and having a press-fit with the ends of said casing, and an indicia displaying cylinder supported for rotative adjustment between said plates, the operation of engaging said plates with said casing also serving to engage said cylinder with said plates.

3. In a lighting system, a base having parallel slots therein, one side of each slot being undercut to provide a locking recess, a U-shaped casing

having resilient side walls with edges flanged to engage in said recesses and maintain the casing in place by virtue of the resilient action of said walls, end plates on said base and having a press-fit with the ends of said casing, an indicia displaying cylinder supported for rotative adjustment between said plates, a gaseous discharge tube extending through said cylinder and having its ends supported in said plates, a transformer within said casing, and electrical connections between said transformer and said tube including conducting elements embedded in said end plates.

4. In a lighting system, a base having parallel slots therein, one side of each slot being undercut to provide a locking recess, a U-shaped casing having resilient side walls with edges flanged to engage in said recesses and maintain the casing in place by virtue of the resilient action of said walls, end plates on said base and having a press-fit with the ends of said casing, aligned bearings in said end plates, a cylinder having its ends journaled in said bearings to form the sole support therefor, said cylinder including an opaque cylindrical segment and lens means disposed between and having interlocking connections with the edges of said segment, and a tubular light source extending through said cylinder and having its ends supported in said plates.

5. In a lighting system, indicia for display, light magnifying means for outlining said indicia from the rearward side thereof, a rod-like source of light adjacent said magnifying means, and light diffusing means between said light source and said magnifying means.

6. In a lighting system, indicia for display, tubular supporting means for said indicia including magnifying lens means for outlining said indicia, and a rod-like source of light disposed within said supporting means in axial alignment, whereby adjustment of said supporting means about said axis does not vary the relation between said light source and said lens.

7. In a lighting system, indicia for display, tubular supporting means for said indicia including a tubular opaque segment and lens means having interlocking connections with the edges of said segment, said lens means serving to outline said indicia, and a source of light disposed within said supporting means.

8. In a lighting system, a lens having an axis of curvature, indicia associated with said lens for outlining by light transmitted through said lens, a gaseous discharge tube disposed parallel to said axis of curvature in symmetrical relation to said lens for transmitting light through said lens, and light diffusing means between said tube and said lens.

9. In a lighting system, a lens having indicia on one surface thereof, a gaseous discharge tube adjacent the other surface of said lens for transmitting light through said lens, and light diffusing means formed on said other surface of said lens.

10. In a lighting system, a frame, a cylinder mounted for rotative adjustment on said frame having an opaque portion and an indicia bearing transparent portion, and a source of light supported by said frame within said cylinder.

11. In a lighting system, a frame, a hollow indicia bearing member mounted for adjustment on said frame to display said indicia in different directions, and a source of light supported by said frame within said member.

12. In a lighting system, a frame having aligned spaced apart bearing portions, a cylinder mounted

for rotative adjustment in said bearing portions, said cylinder comprising an opaque segment and indicia bearing lens means mounted thereon, and a source of light extending through said cylinder and supported by said frame.

- 5 13. In a lighting system, a frame having aligned spaced apart bearing portions, a cylinder mounted for rotative adjustment in said bearing portions, said cylinder comprising an opaque segment and indicia bearing lens means mounted thereon, an 10 electrically operated source of light extending

through said cylinder and supported by said frame, and electrical connecting means for said source of light carried by said frame for operative engagement with the terminals of said source of light upon mounting thereof.

- 5 14. In a lighting system, tubular display means including a light-transmitting magnifying segment and an opaque segment having their edges in interlocking engagement, and a source of light disposed within said display means.
